UNITED STATES PATENT OFFICE.

CARL W. PITLICK, OF OAHE, SOUTH DAKOTA.

HOG-RESTRAINING DEVICE.

1,381,006.

Specification of Letters Patent. Patented June 7, 1921.

Application filed September 19, 1919. Serial No. 324,302.

To all whom it may concern:

Be it known that I, CARL W. PITLICK, a citizen of the United States, residing at Oahe, in the county of Hughes, State of 5 South Dakota, have invented a new and useful Hog-Restraining Device; and I do hereby declare the following to be a full, clear, and exact description of the invention, such as will enable others skilled in the art to 10 which it appertains to make and use the same.

The invention relates to restraining devices whereby hogs may be held in such a position that their heads will extend outwardly between pivoted bars so that a conventional form of snout holding device may be applied thereto, for holding the snout in such a position that a ring may be passed through the same.

20 A further object is to provide a gangway over which the hogs pass and to provide one end of the gangway with a tilting platform whereby as the same is tilted the hog will slide forwardly to a position where the head 25 will project between the pivoted bars. Also to provide means so that when the platform is tilted a hog that may be following in the gangway will be prevented from entering the compartment in which the pivoted plat- 30 form is located.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:—

Figure 1 is a side elevation of the device showing the platform in horizontal position.

Fig. 2 is a longitudinal sectional view showing the platform in tilted position.

45 Fig. 3 is a perspective view of the end carrying the pivoted bars.

Fig. 4 is a detail sectional view of the detent means for the pivoted bars.

Referring to the drawings, the numeral 1 50 designates a gangway, which gangway comprises the inclined section 2 and the horizontal section 3, which sections 2 and 3 are secured together by means of a rod 4, which passes through overlapping eyes 5. The 55 other end of the section 3 is secured by means of hooks and eyes 6 to the rearwardly ex-

tending portion 7 of the platform section 8 of the gangway. One end of the section 8 is provided with a partition 9 having apertures 9^a in the ends thereof, adapted to register with an aperture in the sides of section 8 and through said apertures pins 9^b pass. The edge of partition 9 is of greater height from the bottom of the section 3 than the height of the hog's back. Pivoted on a 60 transversely disposed shaft 11 is a platform 12, said platform being provided with a weight 12^b. This platform 12 is adapted to be tilted from its position as shown in Fig. 1 to its position shown in Fig. 2, that is 70 after a hog has passed from the section 3 onto the tilting platform 12, said tilting being accomplished by the weight of the hog or by means of a lever 13 on one end of shaft 11. Weight 12^b returns the platform to normal horizontal position after each hog holding and releasing operation. A hog passes onto the tilting platform 12, then before another hog can pass onto the same from the section 3, the platform 12 tilts thereby bringing the curved portion 16 into registration with the passage under the partition 9 thereby preventing the second hog from passing onto the tilted platform and keeping him away from the compartment of the section 8. 75 The platform 12 is limited in its upward movement by the cleat 17 and in its downward movement by the cleat 18 and stop 19.

When the hog passes onto the tilting platform 12, the same is tilted which causes the 90 hog to slide head first toward the opening 20 and his head to be in a position where it will come through between the pivoted levers 21, said levers being pivoted as at 22 at their lower ends and provided with dogs 95 21^a which are adapted to coöperate with a toothed rack 21^b whereby the opening between the levers 21 may be quickly varied according to the size of hogs, that are being used. The hog's head being disposed 100 and held between the levers 21, a snout engaging loop is then passed around the snout and therefore the hog's head and snout held in position wherein it will be easy for a ring to be passed through the nose.

105 The invention having been set forth what is claimed as new and useful is:—

1. In a device of the character described comprising a gangway and a tilting platform section, the inner end of the gangway 110 section being provided with a partition having an animal passage under the same, a tilt-

ing platform horizontally pivoted within the platform section and in horizontal alignment with the flooring of the gangway section, means whereby said tilting platform 5 will tilt as the animal moves over the same thereby sliding the animal toward the lower end thereof when the same is inclined, an adjustable head engaging opening in the end of the tilting platform section and adapted 10 to receive the animal's head, and a downwardly extending curved member concentric with the pivotal point of the tilting platform and carried by the rear end of the tilting platform and adapted to register with 15 the passage under the partition at the end of the gangway section when the platform is tilted thereby preventing animals that may follow on the gangway section from entering the pivoted platform section after the 20 platform has been tilted.

2. A device of the character described comprising a gang way and a tilting platform section, inner end of the gang way section being provided with a partition having 25 an animal passage under the same, a tilting platform horizontally pivoted within the platform section and in the same horizontal

plane as the flooring of the gangway section, the rear end of said tilting platform being in engagement with the end of the 03 gangway flooring, a downwardly extending curved portion carried by the rear end of the tilting platform, said curved portion being concentric with the pivoted point of the platform, weight means disposed between 35 the downwardly extending curved portion and the pivotal point of the platform said weight means forming means for tilting the platform to normal horizontal position, stops for limiting the downward movement 40 of the forward end of the platform at a point where its rear end will be adjacent the lower end of the partition and means for adjusting said partition for limiting the upward movement of the rear end of the platform. 45

In testimony whereof I have signed my name to this specification in the presence of two subscribing witnesses.

CARL W. PITLICK.
